UNITED STATES PATENT OFFICE

155,950

DESIGN FOR A CREEPER OR THE LIKE

William T. Williams, Johnson City, N. Y., assignor
to Endicott Johnson Corporation, Endicott,
N. Y., a corporation of New York

Application May 31, 1949, Serial No. 2,978

Term of patent 14 years

(Cl. D7—7)

To all whom it may concern:

Be it known that I, William T. Williams, a citizen of the United States, residing at Johnson City, county of Broome, State of New York, have invented a new, original, and ornamental Design for a Creeper or the like, of which the following is a specification, reference being had to the accompanying drawing, forming a part thereof.

In the drawing:

Figure 1 is a top plan view of a creeper or the like, showing my new design;

Fig. 2 is a side elevation thereof;

Fig. 3 is a rear end elevation thereof.

I claim:

The ornamental design for a creeper or the like, substantially as shown.

WILLIAM T. WILLIAMS.
